DESIGN FOR A SHOE OR SIMILAR ARTICLE

Samuel L. Kleven, Augusta, Maine

Application October 26, 1946, Serial No. 134,303

Term of patent 3½ years

(CL. D7—7)

To all whom it may concern:

Be it known that I, Samuel L. Kleven, a citizen of the United States, residing at Augusta, in the county of Kennebec and State of Maine, have invented a new, original, and ornamental Design for Shoe or Similar Article, of which the following is a specification, reference being had to the accompanying drawing, forming part thereof.

Figure 1 is a perspective view of a shoe or similar article, showing my new design, and

I claim:

The ornamental design for a shoe or similar article, substantially as shown.

SAMUEL L. KLEVEN.
